UNITED STATES PATENT OFFICE.

EUGENE THOMAS ROBESON, OF SWANSBORO, NORTH CAROLINA.

MINE-DESTROYING MEANS.

1,187,179.

Specification of Letters Patent. Patented June 13, 1916.

Application filed December 18, 1915. Serial No. 67,578.

To all whom it may concern:

Be it known that I, EUGENE T. ROBESON, a citizen of the United States, and a resident of Swansboro, in the county of Onslow 5 and State of North Carolina, have invented a new and Improved Mine-Destroying Means, of which the following is a full, clear and exact description.

An object of my invention is to provide 10 a mine-destroying means including a pilot boat and a conveyer or charge-carrying boat adapted to carry an explosive charge for exploding the mine, the respective boats to be equipped with means whereby to automatically control the direction thereof as 15 well as their relative speeds.

A further object of the invention is to provide a mine-destroying means of the character described in which the explosive 20 charge will be carried and automatically connected with a mine and exploded.

Other important objects and the advantages of my invention will appear from the following description.

Reference is to be had to the accompanying drawings forming a part of this specification in which similar reference characters indicate corresponding parts in all the views.

Figure 1 is a perspective view of a pilot boat and a charge-carrying boat and their appurtenances, embodying my invention; Fig. 2 is a similar view to be hereinafter referred to, the view being given to indicate 35 the manner in which the charge-carrying boat is caused to round a mine after the mine cable has been engaged and is so close to the charge-carrying boat as to require the latter to make a short turn in order to connect the explosive charge with the mine; Fig. 3 is a perspective view showing the charge applied to the mine, and the conveyer boat leaving the mine to explode a charge; Fig. 4 is a fragmentary plan view 40 of the conveyer boat; Fig. 5 is a longitudinal vertical section of the conveyer boat; Fig. 6 is a horizontal section on the line 6—6, Fig. 5; Fig. 7 is a transverse vertical section on the line 7—7, Fig. 5; Fig. 8 is a 45 fragmentary perspective view of a means for throwing the main propeller out of action when the conveyer boat unduly advances relative to the pilot boat; Fig. 9 is a vertical section on an enlarged scale of the 50 mine-carrying charge and the depending 55 mine-carrying charge and the depending

stem on the conveyer boat by which said charge is carried and through the medium of which the conveyer boat is automatically controlled upon a mine cable being engaged; Fig. 10 is a horizontal section on the line 60 10—10, Fig. 5; Fig. 11 is a horizontal section on the line 11—11, Fig. 5; Fig. 12 is a horizontal section on the line 12—12, Fig. 5; Fig. 13 is a horizontal section on the line 13—13, Fig. 5; and Fig. 14 is a perspective 65 view of a device relating to the charge releasing mechanism.

In carrying out my invention in accordance with the illustrated example, a pilot boat 10 is provided and a conveyer boat 11 70 to carry an explosive charge. Both boats are connected by an underwater drag cable 12 and by an overhead cable 13. The pilot boat is equipped with a rudder or rudders 14 on a depending stem 15, and the conveyer 75 boat 11 is equipped with a rudder or rudders 16 on a depending rudder stem 17. The pilot boat is provided with a stern propeller 18 driven by any source of power within the boat or from an electric current from a boat 80 following astern of the pilot and conveyer boats. Similarly, the conveyer boat is provided with a stern propeller 19.

The drag cable 12 is connected at one end with a forward arm 20 on the rudder stem 85 15 of the pilot boat and at its opposite end to a similar arm 21 on a stem 22, depending from the conveyer boat adjacent to the rudder stem 17. The several stems, 15, 17, 22, 90 are tapered at the front to offer the minimum resistance.

The stem 22 is mounted at its upper end to turn on its own axis and the turning of the stem controls a steering gear which may consist of a sector 23 on the upper end of the stem above the deck of the conveyer boat 11, said sector meshing with a sector 24 on the rudder stem 17. The sector 23 has an arm 25 connected with a retractile spring 26 of sufficient strength to normally 100 maintain the stem 22 and the rudder stem from turning. The rudders of the respective boats are set at such an angle as to cause the boats to tend to move away from each other and thereby maintain the cables 12 105 and 13, substantially taut and the spring 26 will have sufficient tension for this purpose.

The propeller 19 of the conveyer boat 11 is driven by an electric motor 27 and I pro- 110

vide means whereby to cut out said motor and to cut in a motor on an auxiliary steering propeller when the drag cable 12 comes in contact with the mine cable, the means shown for this purpose, being as follows: Connected at one end to the stem 22 is a strap 28, or the like, which may have a coil spring therein to permit it to yield and give a gradual action. The said strap connects 10 with a switch arm 30 operating between contact elements 31, 32. Upon the cable 12 contacting with the cable *a* of a mine A, the resistance will result in turning the stem 22 by the cable 12 exerting a pull on the arm 21, 15 and the turning of the stem 22 will, through the steering gear elements 23, 24, turn the rudder stem 17 and swing the rudders 16 to direct the boat in the direction of the pull on the cable 12. The charge conveyer boat 20 11 is thus caused to round the mine and to automatically attach an explosive charge to the mine cable as hereinafter explained.

In the event the conveyer boat 11 is too close to the mine A, to round the same by a 25 gradual turning movement, the increasing pull of the drag cable 12 on the arm 21 will continue the turning movement of the stem 22 and will wind up the strap 28 sufficiently to throw the switch arm 30 away from the 30 contact member 31 which conducts the current to the motor 27 of the stern propeller 19, thus cutting out said motor. At the same time the swinging of the switch arm 30 will effect contact with the member 32 which 35 controls the current from storage batteries 33 or other source to an auxiliary motor 36 on a transverse propeller shaft 37 carrying a side propeller 38. The current may be supplied by a wire 33^a (Fig. 5) running, in 40 practice, from a boat following, and not here shown. The stopping of the motor 27 brings the conveyer boat practically to a standstill with the exception of a movement conveyed to it by the pilot boat 10. The conveyer 45 vessel will be held in place by the drag cable 12 and the starting of the auxiliary motor 36 and side propeller 38 will result in the stern of the vessel being swung around until the boat is headed in the direction of the pull on 50 the cable 12. As the vessel is forced about by the side propeller the stem 22 is held in practically stationary position and acts as an axis in the turning of the conveyer boat until the latter has assumed its normal position 55 relatively to the stem 22 and strap 28 controlling the switch. As the boat turns the gradual unwinding of the strap 28 or equivalent flexible element, connecting with the switch arm 30, will release the switch arm 60 permitting the spring 34 to throw the switch to the contact 31 thus again throwing in the motor 27 controlling the stern propeller 19 and cutting out the side propeller so that the boat will move forward in the direction of 65 the pull and round the mine A and its

cable *a*. The strap 28 runs over suitable guide sheaves 35.

The upper cable 13 is secured at one end to a fixed post 39 on the pilot boat and at the opposite end is fixed to a corresponding post 40 on the charge conveyer boat 11. The cable thus tends to prevent turning or rolling of either boat in a direction away from the other. In order to insure that the conveyer boat 11 shall at all times and under all circumstances keep up with the pilot boat 10, I give the conveyer boat slightly higher speed, a ratio, for example, of 4 to 3. The relative excess of speed of the conveyer boat will frequently cause it to pass the pilot boat and I utilize the cable 13 to stop the propeller of the conveyer boat when it passes the pilot boat to a predetermined extent. Branch cables 41, 42, extend respectively from the cable 13 to the boats 10, 11, and the cable 42 is passed through an arm 43 near the outer end of the latter, and made fast as at 44 in any suitable manner to the hull of the boat 11. The arm 43 is secured as at 45 to a vertical rod or shaft 46 which extends to the interior of the boat 11 and is formed with a lateral arm 47 which may be produced by bending the end of the said rod upwardly. To the arm 47 is connected one end of a pull-cord or wire 49, which passes through suitable guides 48 to a connection with a switch arm 50, said switch arm being connected with a retractile spring 51, and controlling a switch 52. The switch 52 will be thrown under the following circumstances: When 10 the conveyer boat 11 runs ahead of the pilot boat, the cable 13, instead of being at right angles to the general direction of travel of the boats, will assume an oblique position, thereby giving a rearward movement to the 15 branch cable 42, relative to the boat 11, causing the arm 43 to be swung rearwardly and turning the rod or shaft 46 through a sufficient angle to exert a pull on the cord or wire 49, thereby throwing the switch arm 10 50 and breaking the electrical connection, thus stopping the motor 27 and the propeller 19. Until the pilot boat makes a relative advance and the cable 33 is again disposed in its normal position, whereupon the retractile 11 spring 51 will restore the switch arm 50 and reestablish the circuit to the motor 27.

On the side of the stem 22 I provide a horizontal fender 53 having a pointed forward end and curving laterally at the outside to deflect the mine cable *a* away from the stem and pass it along the side of said fender. The fender may be secured by clamps 54 to the stems 17 and 22. The function of the fender 53 also, is to hold the stems 17 and 22 from contacting with the firing points on the mine. It will be understood that in practice, the fender may have any width necessary and the grab 71 will be disposed accordingly at the proper dis- 12

tance outward from the stem 22 to have the mine cable guided to said grab by the fender.

The stem 22 may be built up of a series of short lengths or sections whereby to extend the same to any desired depth, the sections having, respectively, tenons 55 and corresponding orifices 56 and the connection being completed by set screws 57, or the like. Also, the sections, or certain of them, may be composed of two side members having a vertical joint 58, the side members of each section being held by clamps 59 and bolts 60. There may be a tongue and groove connection 61 at the joint 58, as indicated in Figs. 11 and 12.

My preferred means for carrying the explosive charge is by a separate shell 62, which will have suitable air ballast compartments 63. The shell 62 is sustained by the stem 22 being adapted to seat laterally against pairs of arms 64 flaring at their outer ends to conform to the adjacent flaring sides of the said shell, which is preferably diamond shape in cross section to minimize the resistance offered by the water. Between each pair of arms 64, a compression spring 65 is located on the stem 22 tending to unseat the shell and force the same away from the stem. To retain the shell on its seat the same is formed with eyes 66 which are engaged by hooks 67, which are provided on a shaft or vertical rod 68, which is adapted to turn in the stem 22. A chain 69 at the lower end of the shell 62 is connected as at 70 to a mine grab 71 adapted to grab a cable α of the mine. To detachably secure the grab 71 to the vertical rod 68 I provide on said grab at a side thereof, a lateral stem 72 which is removably received in a corresponding lateral socket 73 in the said rod 68. The grab 71 is in the form of a horizontal frame, the open end of which is provided with closure arms 74 pivoted near their outer ends at 75, and the outer ends being connected with retractile springs 76 tending to maintain the arms in closed position subject to contact with a mine cable, whereby the pressure of the cable will force inward one, or both, of the said arms 74 permitting the mine cable to enter the said grab. As the mine cable enters the grab and contacts with the rear wall thereof, the pressure of the said cable will tend to turn the rod 68 and permit the release of the said grab. The arm 72 extends through a fork 77 on the stem 22, the said fork facing rearwardly, and a compression spring 78, encircling the stem 72 of the grab, bears at one end laterally against the adjacent side of the rod 68 and at the outer end against a shoulder 80 on the stem 72, thereby tending to force said stem outwardly with the shoulder against the inner side of the fork 77. The stem 22 is slotted 65 adjacent to the fork 77 to permit turning of

the shank or stem 72 with the turning of the rod 68. Therefore, upon the rearward movement of the grab 71, as soon as the shank 72 is clear of the fork 77, the spring 78 will force the grab and its shank 72 outwardly, 70 thus detaching the grab from the rod 68. Simultaneously, with the release of the grab the explosive shell 62 is released from the hooks 67 since by the turning movement of the rod 68, which will turn the said hooks 75 67, carried thereby, out of the eyes 66 of the shell, permitting the springs 65 to unseat the shell and force it away from its seat 62 on the stem 22. The shell which is buoyant by reason of the air compartments 63, may now 80 rise on the mine cable α until the grab 71 is arrested by the mine A. The stem 22 has slots 81 adjacent to the hooks 67 to permit the turning movement of said hooks with the rod 68 in releasing the eyes 66.

In order to automatically effect the explosion of the charge after the conveyer boat 11 has moved away from the same a predetermined distance after attaching the explosive charge, an electric conductor 82 leads 90 from the explosive charge through a hawse-hole or opening 83 (Figs. 5 and 7), in the side of the boat to the interior of the latter and passes about a suitable drum, or drums, 84 on which the said conductor is wound. 95 The conductor 82 is insulated but at the forward terminal thereof or at a suitable point thereon, a metallic contacting flange or head 85 is produced. The wall of the hawse-hole 83 is electrically charged by suitable 100 electric connection with the batteries 86 or other source of electricity so that upon the boat 11 having traveled a sufficient distance to bring the contact member 85 against the walls of the hawse-hole, an electric current will flow 105 to the firing charge and explode the same.

The boat will be provided with a suitable keel 87. Also, the hull of the conveyer boat 10 is provided with suitable stuffing boxes 88, 89 for the stems 17, 22.

It will be seen from the foregoing that the cable connections between the boats serve to synchronize the movements of the boats and also serve to control the turning movement of the conveyer boat and that, when the dragging cable 12 is arrested by engagement with a mine the continued movement of the pilot boat consists in directing the movement of the conveyer boat to the mine. 115 As the conveyer boat rounds the mine A the fender 53 guides the mine cable laterally to the pivoted arms 74 of the grab 71, and the said mine cable entering the grab will automatically release the charge container and the grab in the manner above described.

Having thus described my invention I claim as new and desire to secure by Letters Patent:

1. A mine-destroying means including a pilot boat, a conveyer boat adapted to carry

- 4
- an explosive charge, a submerged mine-dragging cable connecting said boats, propelling means for said boats, and means connected with said cable and controlling the propelling means of the conveyer boat and adapted to act on the propelling means when the resistance of a mine is offered to the said cable.
6. A mine-destroying means including a pilot boat, a conveyer boat adapted to carry an explosive charge, a cable connecting said boats, propelling means for said boats, and means controlling the propelling means of one of said boats and subject to displacement of said cable by undue relative travel of the boats.
7. A mine-destroying means including a pilot boat, a conveyer boat adapted to carry an explosive charge, propelling means for said boats, a submerged drag cable connecting the said boats, a steering propeller on the said conveyer boat, means for actuating said steering propeller, and means controlled by said cable to throw the main propelling means of the conveyer boat out of operation and throw the steering propeller into operation when the resistance of a mine is offered to the said cable.
8. A mine-destroying means including a pilot boat, a conveyer boat adapted to carry an explosive charge, propelling means for said boats, an overhead cable connecting the said boats, a branch cable extending from said overhead cable, a movable arm on the conveyer boat in engagement with said branch cable, and means controlled by the movement of said arm to throw the propelling means of the conveyer boat out of operation by displacement of the cable due to undue relative movements of the boats.
9. A mine-destroying means including a pilot boat, a conveyer boat adapted to carry an explosive charge, propelling means for said boats, submerged depending stems on the said boats, lateral arms on the said stems, a cable connecting the said arms, the stem of the conveyer boat being adapted to be turned by said cable when meeting resistance of a mine, and means actuated by the turning of the stem on the conveyer boat to control the propelling means of the conveyer boat.
10. A mine-destroying means including a pilot boat, a conveyer boat adapted to carry an explosive charge, propelling means for said boats, submerged depending stems on the said boats, lateral arms on the said stems, a cable connecting the said arms, the stem of the conveyer boat being adapted to be turned by said cable when meeting resistance of a mine, a steering propeller on the conveyer boat, and means actuated by the turning of the stem on the conveyer boat to throw the propelling means and the steering propeller into and out of operation.
11. A mine-destroying means including a pilot boat, a conveyer boat, a submerged cable connecting said boats, propelling means for the said boats; means controlled by the
12. A mine-destroying means including a pilot boat, a conveyer boat adapted to carry an explosive charge, submerged depending stems on the said boats, a drag cable connecting the said stems, means to detachably mount an explosive container on the stem of the conveyer boat, the container having means to connect the same with a mine, propelling means for the said boats, means on the conveyer boat and subject to the said cable to direct the said conveyer boat in the direction of a pull on the cable when the said cable is engaged with a mine, and means controlled by said cable to release the container when its attachment means engages a mine.
13. A mine-destroying means including a pilot boat, a conveyer boat, a submerged cable connecting said boats, propelling means for the said boats, means controlled by the cable to turn the conveyer boat when the cable is obstructed by a mine, a container adapted to carry an explosive material, means to detachably secure the container to the conveyer boat, means connected with the container to engage a mine cable, and means for releasing said container and its said mine-engaging means when the last-mentioned means engages the cable.
14. A mine-destroying means including a pilot boat, a conveyer boat having a submerged depending stem mounted to turn, a cable connected with said stem and with the pilot boat, a vertical rod mounted to turn in the said stem, a container adapted to hold an explosive charge, means on the stem to hold said container, a grab connected with the container and adapted to engage a mine cable, means on the said rod to detachably hold said grab, said rod being adapted to be turned by the grab when engaged and being resisted by a mine cable, and means to release the container and grab by the turning of the said rod.
15. A mine-destroying means including a pilot boat, a conveyer boat, a submerged drag cable connecting the said boats, a container adapted to hold an explosive charge, means on the conveyer boat to hold the said container, means connected with the container and adapted to engage a mine, means to automatically release the container and its mine-engaging means and attach the latter to a mine cable when the drag cable engages the mine cable, an electric conductor attached to the said container to explode the charge thereof, means on the conveyer boat to pay out said electric conductor, and means to establish an electric circuit through said conductor when paid out to a predetermined extent.
16. A mine-destroying means including a pilot boat, a conveyer boat, a submerged cable connecting said boats, propelling means for the said boats; means controlled by the

cable to turn the conveyer boat when the cable is obstructed by a mine, a container adapted to carry an explosive material, means to detachably secure the container to the conveyer boat, means connected with the container to engage a mine cable, a guide fender positioned on the conveyer boat to direct a mine cable to the mine-engaging means, and means for releasing said con-

tainer and mine-engaging means when the latter engages the mine cable.

In testimony whereof I have signed my name to this specification in the presence of two subscribing witnesses.

EUGENE THOMAS ROBESON.
